UNITED STATES PATENT OFFICE.

LOUIS J. KRIVOHOLANY, OF MASON CITY, IOWA.

TORPEDO.

1,217,016.

Specification of Letters Patent. Patented Feb. 20, 1917.

Application filed February 18, 1916. Serial No. 79,216.

To all whom it may concern:

Be it known that I, LOUIS J. KRIVOHOLANY, a citizen of the United States, residing at Mason City, in the county of Cerro Gordo and State of Iowa, have invented new and useful Improvements in Torpedoes, of which the following is a specification.

This invention relates to certain novel and useful improvements in torpedo construction.

In carrying out the present invention, it is my purpose to provide a torpedo wherein the magazine may be exploded upon the head of the torpedo striking the target and wherein the shell of the torpedo will be braced against collapsing when the head end of the torpedo strikes the object, thereby enabling the powder in the magazine to exert its full pressure to explode the shell.

It is also my purpose to provide a torpedo which may be discharged from the tube under the full air pressure, which will travel at great speed toward the target or object to be struck and wherein the fulminating cap and magazine will remain intact until the torpedo strikes the object head-on, thereby preventing premature exploding of the torpedo.

With the above and other objects in view, the invention consists in the construction, combination and arrangement of parts hereinafter set forth in and falling within the scope of the claim.

In the accompanying drawings:

Figure 1 is a view in side elevation of a torpedo constructed in accordance with my present invention.

Fig. 2 is a longitudinal sectional view therethrough.

Fig. 3 is a cross sectional view through the same.

Fig. 4 is a perspective view of the bracing bar removed from the torpedo.

Fig. 5 is a view in elevation of the impact rod and the spider on such rod.

Referring now to the drawings in detail, 1 designates a shell which is preferably cylindrical in cross section and threaded into one end of the shell and suitably secured thereto is a base 2 projecting beyond the end of the shell and having the outer cylindrical wall thereof flush with the outer wall of the shell and formed with annular grooves spaced apart to receive packing rings 3 adapted to fit against the wall of the air tube during the discharge of the tor-

pedo so as to prevent leaking of air past the torpedo and enable the full pressure of the air to act on the torpedo so that the latter will be expelled from the tube at great speed. Secured to the remaining end of the shell 1 is a cone-shaped head 4. Arranged within the shell 1 is a magazine 5 containing a high explosive and the ends of the magazine 5 are preferably rounded. The end of the base 2 confronting the rounded end of the magazine is convexed as at 6 and within this convexed end of the base, the rounded end of the magazine is seated. Interposed between the head 4 and the adjacent end of the magazine 5 is a filler 7 of lead or other suitable material conforming to the shape of the head and the end of the magazine so as to hold the magazine against movement within the shell. Secured to the end of the magazine within the head is a priming cap 8, while formed in the filler 7 and the apex of the head are coaxial bores. Passed through these bores is an impact rod 9 having the inner end abutting the cap 8 and the outer end projecting beyond the apex of the head and secured to the outer end of the impact rod is a spider 10 adapted to strike the target or object in the path of the torpedo. Passed through the impact rod 9 is a cross pin 11 having the ends thereof embedded in the filler 7 and this pin 11 acts to hold the rod 9 against accidental inward movement and when the outer end of the rod and the spider 10 thereon strike against a vessel or other target, the rod 9 is forced inwardly and the pin 11 broken so as to release the rod and the inner end of the rod explodes the priming cap 8 and the heat and sparks from the priming cap ignite the powder in the magazine 5 with the effect to explode the torpedo and so damage the vessel or other target.

In order to reinforce the shell so as to prevent the collapsing thereof when the head end of the torpedo strikes the target, I employ a longitudinal bar 12 arranged centrally of the magazine and having one end seated against the concaved end of the base 2 and the other end terminating short of the head end of the magazine and provided with outwardly diverging arms 13 projecting through the head end of the magazine and embedded in the filler 7. The end of the rod 12 adjacent to the base 2 is formed with a bore 14 and threaded through the base 12 and into the bore 14 is a holding

screw 15. The arms 13, the bar 12 and the screw 14 coöperate with one another to reinforce the shell 1 so as to prevent collapsing of the shell when the head strikes the target. Thus, the possibility of premature explosion is avoided and the powder in the magazine when ignited may explode and develop its greatest pressure.

While I have herein shown and described the preferred form of my invention by way of illustration, I wish it to be understood that I do not limit or confine myself to the precise details of construction herein described and delineated, as modification and variation may be made within the scope of the claim and without departing from the spirit of the invention.

I claim:

A torpedo comprising a shell, a magazine within said shell, a cap for exploding the

contents of said magazine, an impact rod having one end bearing against said cap and the other end projecting through said shell, a filler surrounding that portion of the rod within the shell, a bar extending longitudinally of the magazine, a connection between one end of said bar and the butt end of the shell, and legs integral with the other end of the bar and diverging outwardly from each other and having the outer ends thereof embedded in said filler and acting to reinforce the shell to prevent the collapsing thereof.

In testimony whereof I affix my signature in presence of two witnesses.

LOUIS J. KRIVOHHLANY.
